OBJECTIVE INDICATOR FOR GAME APPARATUS

Jerry C. Koci, Chicago, Ill., assignor to Chicago Coin Machine Mfg. Co., Chicago, Ill., a corporation of Illinois

Application November 22, 1940, Serial No. 366,519

1 Claim. (Cl. 273—118)

This invention relates to a game objective indicator and has for its principal object the provision of an improved construction of this character which will be highly efficient in use and economical in manufacture.

Among the several objects of this invention is the provision of a combination and arrangement of parts arranged in an electric circuit under the control of bumper contact means and which when operative is caused to indicate by illumination a game objective.

Another object of the invention is to provide a game objective indicator, the indication of which is the result of illumination, thereby increasing the eye appeal of the game to the player.

Another object of the invention is to provide a game objective indicator which may be associated in combination with other objectives of the game in a variety of different combinations.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a plan view of a typical game board illustrating my game objective indicator associated therewith;

Fig. 2 is an enlarged sectional detail view of the same taken substantially on line 2—2 of Fig. 1;

Fig. 3 is a fragmentary plan view of the play-board of the game apparatus illustrated in Fig. 1 looking toward the underside thereof; and

Fig. 4 is a diagrammatical view of a preferred electric circuit showing my improved game objective indicator associated therewith.

I have heretofore indicated that my improved game objective indicator may be associated in various combinations with other mechanisms of a game apparatus, and I therefore do not want to be limited to any one particular combination, but desire to avail myself of the right to employ my improved game objective indicator in the various combinations in which it can be incorporated without departing from the spirit of the invention.

Referring particularly to the drawings, the conventional game apparatus includes a cabinet 10 usually provided with an inclined playboard 11, toward the upper end of which balls are preferably projected for gravitation theredown by a ball projector 12. The inclined board 11 is usu-

ally disposed beneath a glass panel (not shown).

My improved game objective indicator includes a ball bumper structure 13 comprising a bumper head 14 of any conventional shape, design and construction. This bumper structure 13 is mounted upon the inclined playboard 11 as at 15 and preferably includes a depending contact arm 16 connected in one side of an electric circuit as at 17 and adapted to engage a fixed contact bracket 18 connected as at 19 to the other side of the electric circuit.

This electric circuit includes a step-up relay 20 operatively related to a ratchet wheel 21 mounted on a shaft 22 carrying a wiper contact arm 23. This arm 23 is adapted to have engagement with contact buttons 24 arranged in an electric circuit comprising conductor members 25 and 25'; each conductor 25 is connected to one side of an electric lamp 26, there being, in the present instance, five of such lamps. These lamps 26 are supported from beneath the inclined board 11 by brackets 27, within suitable openings 28 formed circumferentially about the bumper structure 13 in the board 11. The bumper structure 13 includes an annular horizontal disc or shield 29, the peripheral edge portion of which is disposed over the openings and is preferably formed of a translucent material to permit light passage therethrough when the electric bulbs 26 are illuminated. This disc 29, in the present instance, is floatingly mounted upon the bumper structure 13 and supports the contact arm 16 whereby when the beveled edge 30 of this disc is impinged by a rolling ball, it will be caused to tilt and consequently bring the conductor arm 16 into contact with the conductor bracket 18.

Preferably adjacent each of the openings 28 and beyond the peripheral edge of the disc 29, the openings are designated by a number, such as indicated at 31.

The conductors 25' are connected to one side of electric score lamps 32; the other side of these score lamps, like the lamps 26, are grounded as at 33.

The energization of the step-up relay 20 which controls the movement of the ratchet wheel 21 in step by step fashion for the purposes herein-after set forth, is controlled by an electric circuit 34, in which there is arranged in parallelism a plurality of bumper structures 35 similar in structure to the bumper structure 13 and, like the bumper structure, each including a conductor arm 36 and a conductor bracket 37 whereby when the conductor arms 36 are caused to pivot

by the action of a ball engaging the disc carrying such arms, a circuit will be momentarily completed to the step-up relay 20, causing the operation of the solenoid 20' thereof. This operation of the solenoid imparts a step by step movement to the ratchet 21, moving the wiper arm 23 onto the next succeeding buttons 24, whereby to illuminate the score lamp 32 and the objective indicator lamp 26 controlled by such buttons as are engaged by the wiper arm 23.

The game apparatus hereinbefore referred to and including the cabinet 10, in addition to including bumper structures like that indicated at 13 for controlling the successive illumination of the game objective lamps 26, also includes other score bumpers 38. These bumpers 38 are of substantially the same structure as the bumpers 13 and control certain scoring mechanism (not shown) included in the game apparatus. In a combination of bumpers such as are indicated at 38, my improved game objective indicator may be employed in the following manner, it being understood that this combination is merely used to show one form of employment of my improved game objective indicator.

When my improved game objective indicator is employed in a game apparatus having bumper switches such as are indicated at 38, these bumper structures may be designated by numbers 1—5, as indicated at 39, and which correspond to the numbers opposite the holes 28, whereby in playing the game unless the particular bumper 38 engaged by a ball is indicated by

the illuminated lamp 26, no score will result or be counted. This is merely one of the many usages to which my improved game objective indicator may be employed.

5 While I have illustrated and described the preferred form of construction for carrying my invention into effect, this is capable of variation and modification without departing from the spirit of the invention. I therefore do not wish 10 to be limited to the precise details of construction set forth, but desire to avail myself of such variations and modifications as come within the scope of the appended claim.

Having thus described my invention, what I 15 claim as new and desire to protect by Letters Patent is.

In a game objective indicator the combination with a game board down which balls are adapted to gravitate, of a bumper switch structure supported by the board and including a transparent switch actuating peripheral shield disposed above the board in spaced parallel relation with respect thereto and adapted to be engaged by said balls, switch means actuated by said shield when the 25 latter is engaged by a ball, a plurality of indicia means circumferentially arranged on said board adjacent said shield; illuminating means for each of said indicia means and supported by the board beneath said shield, and means controlled by 30 said switch means for successively illuminating said illuminating means.

JERRY C. KOCL
